ASSIGNORS TO CROMPTON & KNOWLES LOOM WORKS, OF WORCESTER, MASSACHUSETTS, A CORPORATION OF MASSACHUSETTS.

CENTER BEARING FOR TUBE FRAMES.

Application filed August 3, 1925. Serial No. 47,738.

This invention relates to tube frames such as are used in Axminster carpet looms, and particularly to the spool bearings thereon. These carpet looms are built to weave very 5 wide fabrics and it is necessary to support several yarn spools on each tube frame. The provision of a simple and effective center spool bearing for such tube frames has been a matter of some difficulty and such center 10 spool bearings have commonly been made with a loose or removable part to permit insertion of the spools.

It is the object of our invention to provide a simple and rigid center spool bearing which 15 may be cheaply and easily constructed and which will be entirely reliable in use.

Our invention further relates to arrangements and combinations of parts which will be hereinafter described and more particularly pointed out in the appended claim.

A preferred form of the invention is shown in the drawings, in which

Fig. 1 is a front elevation of a tube frame having our improved bearings applied there- 25 to,

Fig. 2 is a sectional plan view of our improved tube frame, partially broken away and taken along the line 2—2 in Fig. 1,

Fig. 3 is a sectional longitudinal elevation, 30 taken along the line 3—3 in Fig. 2,

Fig. 4 is a sectional transverse elevation, taken along the line 4—4 in Fig. 2,

Fig. 5 is a partial sectional front elevation of the outer end portion of one of the spools, 35

Fig. 6 is a plan view of a spring used in our improved center bearing, and

Fig. 7 is an end view thereof, looking in the direction of the arrow 7 in Fig. 6.

Referring to the drawings, we have indicated 40 a tube frame comprising the usual rectangular tubular metallic member 10 to which are secured the yarn tubes 11 and the end bearing brackets 12. A series of yarn spools S, S' and S² are mounted on each tubular member 10, with the outside bearings of the end spools supported in the brackets 12 and with the intermediate bearings of the spools supported in our improved center bearings, indicated generally by the letter C.

In the preferred construction, each center bearing C comprises a pair of plates 20 and 21 which are welded or otherwise permanently secured together and which are provided with out-turned lower ends forming a lateral-

ly extended base portion 22. The plates 20 55 and 21 are recessed at both sides adjacent the base 22, as indicated at 23 in Fig. 4, and for a purpose to be described. Each pair of plates 20 and 21 are provided with a plain cylindrical opening 24, which forms a bearing 60 for the adjacent inner end portions of two yarn spools, as S and S'.

A casing or guideway 25 is secured to the upper side of the tubular member 10 by screws 26 or in any other convenient manner 65 to form with the adjacent part of the tube frame a substantially closed compartment for the base 22. Said casing is provided with an elongated slot or opening 27 fitting the recessed lower end of the plates 20 and 21. 70 The base 22 forms a sliding fit within the casing 25 and is thus guided for movement longitudinally of the tube frame.

A spring 28 is placed in the casing 25 at one end of the base 22, as indicated in Figs. 2 75 and 3, and acts to move the center bearing yieldingly to the opposite end of the slot or opening 27. The ends of the spring 28 may be flattened out, as indicated at 29 in Fig. 7, to provide a better bearing against the base 80 22 and the end of the casing 25. The intermediate ends of the spools are commonly provided with interlocking cylindrical portions, as indicated at 30 and 31 in Fig. 3.

The spool S may be placed in position by 85 sliding the center bearing C to the left sufficiently to permit the outer bearing of the spool to be placed in the end bracket 12 and to permit the intermediate bearing member 30 to be aligned with the opening 24. The 90 center bearing C is then released and is moved by the spring 28 toward the spool S until the member 30 is seated in the center bearing. One or more intermediate spools S' may then be placed in position by similar operations 95 and the end spool S² is commonly provided with a spring plunger 33, as indicated in Fig. 5, which may be pressed back into the spool to permit insertion thereof in the end bearing bracket 12.

When assembling the device the bearing is turned around a quarter turn from the position shown in Fig. 2 and the upper part of the bearing passed upwardly through the opening 27. When the recesses 23 are opposite the top of the casing 25 the bearing is turned to substantially the position shown in Fig. 2. To facilitate said turning di- 100 105

agonally opposite corners of the recesses are rounded as at 34. The said reduced portion of the bearing lying between the recesses is approximately the same width as the slot 27 but the latter is somewhat longer than the upper part of the bearing C. Because of the position of the rounded corners 34 it is possible to form the bearing of two similar plates which are stamped alike.

10 We have thus provided a construction by which a series of yarn spools may be readily mounted upon a tube frame and in which each of the center bearings C is formed substantially as a single piece of material having a 15 plain cylindrical bearing opening with a continuous cylindrical surface and having no loose or removable parts involved in the construction thereof.

When the spools are all in position, as indicated in Fig. 1, it is impossible for the center bearings C to move out of operative position and it is impossible for the bearing members 30 or 31 of the spools to escape from the bearing openings 24 in said center bearings C.

25 Having thus described our invention and

the advantages thereof, we do not wish to be limited to the details herein disclosed otherwise than as set forth in the claim, but what we claim is:

30 An Axminster tube frame having a tubular metal body portion, a casing secured to the outside of said body portion and having an outer wall spaced from said body portion and provided with an elongated opening 35 intermediate the ends of the casing, and a member providing a center bearing between two yarn spools and mounted in said casing for sliding movement longitudinally of said tube frame and formed of two similar plates 40 each having a perforated vertical portion to provide a bearing and each provided with a horizontally extending foot, said plates being secured together with the feet extending in opposite directions so that the perforated upright portions of the bearing lie intermediate the ends of the feet and extending up through the opening in said casing.

45 In testimony whereof we have hereunto affixed our signatures.

GEORGE D. LOCKWOOD.
JOHN G. SODERBERG.
